UNITED STATES PATENT OFFICE

2,470,690

CONCRETE STEP FORM

Frederick A. Dahle, Los Angeles, Calif.

Application September 23, 1946, Serial No. 698,765

8 Claims. (Cl. 25—118)

1

This invention is a form for the casting of cement stairway steps, one at a time completely.

It is an object of this invention to provide a simple, substantial, practical and low cost casting form in the matrix of which there may be thoroughly tamped a suitable Portland cement mix for the production of a single, complete step unit for a flight of duplicate steps in a proposed structure.

Also, an object of the invention is to provide a step casting form in which there is a combination of elements cooperative to provide the necessary matrix chambers to give to the cast step the desired limbs and tread, and to provide a form in which several of the combination elements are adapted for ready adjustment as to each other and as to a main core body for making steps having various length, tread and riser dimensions.

Further, a purpose of the invention is to provide a compact and bodily portable step form, and which incorporates matrix making features which can be readily manipulated to quickly release the cast and hardened, monolithic step as produced in the form.

The invention resides in certain advancements in this art as set forth in the ensuing disclosure and having, with the above, additional objects and advantages as will be made manifest in the following description of the herewith illustrative form and its mode of operation; it being understood that modifications, variations and adaptations may be resorted to within the scope, spirit and principles of the invention as it is claimed in conclusion hereof.

Figure 1 is a perspective of a monolithic step as produced by the form here set forth.

Figure 2 is a broken-away, sectional plan of the form.

Figure 3 is a detail, longitudinal section of abutted nose channels of the form.

Figure 4 is a broken-away front elevation of the form.

Figure 5 is a cross-section on line 5—5, of Fig. 2.

Figure 6 is a vertical section of the tread wing matrix parts.

For nomenclature it is desirable to refer to the cast step shown in Fig. 1 and which has a tread T of desired thickness with a front nose FN and an end nose EN for finish effect, and the opposite end of the tread has a vertical wing W with forwardly pitched end faces to facilitate jointing of a string of the finished monoliths. Along the back of the tread is a riser R leading from the wing W to the opposite end of the tread and there having a reverse direction wing RW. In Fig. 5 the step is

2

shown in cross-section in the form matrix (the step being cast in the inverted position in the instant method); where it will be seen that the front nose is considerably deeper than the thickness of the tread per se.

As clearly shown in Fig. 5, the form embodies a stiff, preferably hollow, thin walled core 2 stably supported on any suitable bench or platform B. The core has an elongate, flat and smooth top 3 onto which a batch of plastic cement is poured to form the desired tread T whose front, longitudinal nose is molded in a semicylindrical, elongate forwardly faced channel 4 which is removably clinched firmly to the core top as by a set of clamps 5. The channel 4 may be of any suitable cross-section.

To form the end nose EN of the tread a like, semicylindrical transverse channel 6 extends forwardly from its abutting junction, Fig. 3, with the back channel 4 and has a flat, end sheet 7 which depends in front of the front or riser wall 2r of the core which it vertically abuts for the creation of a matrix pocket 8 in which to form the riser wing RW. The opposite side of this pocket 8 is provided by way of a vertical, transverse flange 9 which is a part of an adjustable means forming an elongate riser pocket 10 in front of the riser wall 2r of the core.

This adjustable means consists of a frontal wall 30 including a set of mutually overlapped plate sections 11, 12 and 13 longitudinally, relatively adjustable on clamp bolts 14 whereby to enable the casting of steps of different lengths at will in this form. As shown in Figs. 4 and 5, the top edge of the sectional wall (11, 12, 13) projects above the top plane of the form top 3 to the level of the horizontal axes of the coplanar nose channels and this determines the thickness of the tread plaster which is compacted and dressed by sweeping a transverse smoothing bar B' longitudinally of the form; Fig. 5. This bar also presses excess plaster out into the fixed nose defining channels mentioned.

The depth of the riser pocket 10 is fixed by a 45 vertically adjustable, longitudinally disposed, spacing strip 15 fixed at the desired level between the front wall 2r of the core and the riser panel or frontal wall 11—13; Figs. 4 and 5. Likewise the depth of the wing pocket 8 is regulated by a forwardly projecting spacing strip 16 abutting the positioned strip 15 and fixed between the outer sheet 7 and the companion flange 9 of the panel or wall 11—13.

To fix the front to rear length of the riser wing 55 pocket 8 a vertical block or stud 17, Figs. 2 and 4,

is clamped between the outer ends of the sheet 7 and the flange 9, and extends up from the rim shaping face 16a of the bottom strip 16 to the level of the top edge of the panel wall 11-13, Fig. 4.

In this disclosure the set up form is provided with a matrix pocket 20, Figs. 4 and 5, to produce the tread wing W on the right-hand end, and means are provided whereby to readily change the tread length and the riser height dimensions as desired for a given step to be cast, and at the same time maintain the end jointing faces J1 and J2 always in parallel, one to the other. To that purpose a vertical wing wall 21 extends down from the top edge of the front panel wall 11-13 to a plane below the bottom of the longitudinal strip 15, Fig. 4, and is spaced from the near end face of the core 2 by a pocket bottom forming spacer device composed of a pair of side lapped slides 22 and 23, Fig. 6. The slide 23 has a horn 23a rigid with its upper end bridging the companion slide 22 and hinged at 23b, Fig. 5, to the bottom edge of the longitudinal nose channel 4; this horn defining the front joint face J1 of the tread wing W, when plastic cement is poured into the pocket 20.

Likewise the lower end of the slide 22 has a horn 22a fixed thereon and bridging the cooperative slide 23 so as to define the back joint face J2, in casting the step. The horn 22a is hinged to the contiguous inner face of the spacer strip 15, Fig. 5. Therefore, as either or both of the tread and the riser widths are preset for a given step monolith the two slides 22-23 (determining the width of the pocket 20) can relatively longitudinally shift, on mutual guides 24, still keeping effective faces of their horns parallel.

It is understood that either right-hand or left-hand steps (as to the wings W and RW) can be cast in this form by mere selection of right or left hand elements; a right-hand set being here shown as assembled onto the core 2. The frontal corners of the core are suitably rabbeted at 2c to produce corner fillets F on the cast step.

In Figs. 4 and 6, is shown a cement stop lug 21a, on the upper rear corner of the wing panel 21, matching the inner face of the nose channel 4; to terminate the relative end of the front nose of the step.

Any suitable and practical means may be employed for temporarily securing the various adjustable pocket forming parts as to the main core 2, and to each other. The nose channel 4 is held to the top of the core as by simple C-strap clamps, and the rear end of the transverse nose channel 6 has a hook 25 interlocking with the channel 4. A spring C-clamp 26 clinches the sheet 7 and the flange 9 onto the interposed spacer strip 16. Suitable spring, C-clamps 27 hold the front panel wall 11-13 to the strip 15 and to the front wall of the core 2. And one or more clamps 28 fix one end of the front wall section 13 to the near, vertical, wing wall 21.

What is claimed is:

1. A concrete step form having, in combination, a block-shaped core presenting a step tread top face and a riser face along one longitudinal side, and right and left end step wing faces for molding a wing on either end of a proposed step; a forwardly facing longitudinally extending nose depth channel bodily shiftable on the said top face toward or from said riser and whose bottom

edge stands on said top face and means for fixedly holding the channel to the said top face, a step end nose channel coplanar with and normal to and abutting the concave side of the longitudinal channel and bodily shiftable on said top face and means for holding the end nose channel on said top face and to the longitudinal channel; a riser panel parallel to and spaced from the said riser face of the core, an elongate riser rim strip

5 forming the bottom of the form space between the core and said panel; a tread wing form wall spaced from an adjacent wing face of the core and abutting the riser panel to close the riser form space and means for holding tread wing wall and said panel in adjusted position on the core, a wing rim form device forming the bottom of the space between the core and said wall; the said panel and said wing wall extending to a desired height above the plane of the said core top and below the top edge of said channels to determine the thickness of the said tread and produce a nose deeper than the tread thickness.

2. The form of claim 1; and means at the opposite end of the tread panel and in front of the riser face of the core box for forming a mold pocket for a back turned riser wing.

3. The form of claim 1; the said riser panel being composed of relatively longitudinally adjustable plates for the casting of steps of different length at will and the end nose channel being adjustable along the longitudinal channel complementally.

4. The form of claim 1; the said riser rim strip being adjustable between the core and said panel toward or from the core top face to produce risers of different heights.

5. The form of claim 1; the said rim device including longitudinally lapping relatively longitudinally adjustable slide sections which are respectively hinged to the top nose channel and to the said strip for concurrent compensating shift during change of tread and riser dimensions.

6. The form of claim 1; the two channels interabutting in a miter, concave joint to point up the intersecting step noses.

7. The form of claim 1; the said device having parallel, wing-facing horns fixed on distal ends of a pair of cooperative, side lapping slide members, and the horns being respectively hinged to the top nose channel and to the said riser rim strip.

8. The form of claim 1; said wing wall having a cement stop lug offset to terminate the frontal nose of the step short of the step riser wing.

FREDERICK A. DAHLE.
